US00D818853S

(12) **United States Design Patent** (10) **Patent No.:** **US D818,853 S**
(45) **Date of Patent:** **** May 29, 2018**

(54) **ACTIVITY MONITORING DEVICE**(71) Applicant: **Fossil Group, Inc.**, Richardson, TX (US)(72) Inventors: **Tim Golnik**, San Francisco, CA (US); **James Toggweiler**, San Francisco, CA (US)(73) Assignee: **Fossil Group, Inc.**, Richardson, TX (US)(**) Term: **15 Years**(21) Appl. No.: **29/578,490**(22) Filed: **Sep. 22, 2016****Related U.S. Application Data**

(60) Division of application No. 29/542,007, filed on Oct. 9, 2015, now Pat. No. Des. 770,314, which is a continuation of application No. 29/512,056, filed on Dec. 16, 2014, now Pat. No. Des. 743,819.

CLAIM

The ornamental design for an activity monitoring device, as shown and described.

DESCRIPTION

FIG. 1 is a perspective view of an embodiment; FIG. 2 is a top view of the embodiment; FIG. 3 is a bottom view of the embodiment; and, FIG. 4 is a side view of the embodiment.

The broken lines immediately adjacent the shaded areas represent the bounds of the claimed design while all other broken lines are directed to environment and are for illustrative purposes only; the broken lines form no part of the claimed design.

1 Claim, 4 Drawing Sheets(56)
